UNITED STATES PATENT OFFICE.

FRANK A. LUNDQUIST, OF CHICAGO, ILLINOIS, ASSIGNOR, BY MESNE ASSIGNMENTS,
TO HENRY S. CONRAD, TRUSTEE.

AUTOMATIC TELEPHONE EXCHANGE.

Application filed July 19, 1917, Serial No. 181,580. Renewed May 13, 1922. Serial No. 560,819.

To all whom it may concern:

Be it known that I, FRANK A. LUNDQUIST, a citizen of the United States of America, and a resident of the city of Chicago, county 5 of Cook, and State of Illinois, have invented certain new and useful Improvements in Automatic Telephone Exchanges, of which the following is a specification.

My invention relates to automatic telephone exchanges and has for its object improvements which will reduce the amount of mechanism involved in the construction and operation of such exchanges.

The improvements in mechanical construction are restricted to the line switches which are individual for the different subscribers, but these changes in construction bring about changes in the organization as a whole. The apparatus at each subscriber's local station 15 is assumed to be the same as that in ordinary use and, as a consequence, the drawings show only the wires leading to such stations. Similarly, the selectors and connectors in the exchange are assumed to be the 20 same as those now in use, and to be operated in the same way. Consequently, the drawings do not go beyond showing the line switches making connection to the bank contacts which lead to first selectors.

30 In the said drawings

Fig. 1, which is largely diagrammatic, represents, at the left, the first or uppermost line switch of a sub-group of one hundred such switches and, at the right, the first line 35 switch of a second sub-group of one hundred such switches. There is intended to be ten such sub-groups to form a group of one thousand subscribers who have common connections to fifty (more or less) trunks leading 40 to a corresponding number of first selectors. Consequently, Fig. 1 represents simply two line switches at the upper left hand corner of a group of one thousand such switches.

Fig. 2 is an enlarged plan of part of the 45 apparatus shown in Fig. 1, but with the contact makers advanced from normal position and moved into contact with a pair of terminals leading to a first selector.

Fig. 3 is a side elevation of the parts 50 shown in Fig. 2.

Fig. 4 is a side elevation of the same parts for the three uppermost switches in one sub-group, together with the shaft upon which they are mounted and the means for operating 55 the shaft.

Fig. 5 is a plan, partly broken away, of the apparatus for moving and holding the shaft of a sub-group.

Fig. 6 is a plan of one of the springs used to return the contact makers to normal position when released.

Fig. 7 is an enlarged face view of a tape having flexible conductors insulatingly imbedded therein.

Fig. 8 is a transverse section still more enlarged, of the tape shown in Fig. 7.

Fig. 9 is an enlarged detail of one of the contact springs together with a part of the disk to which it is connected.

In said drawings, 10 is a shaft on which 70 are secured one hundred disks 11 each having thereon two or more contact springs 12 which also serve as abutments as will be hereinafter described. These parts are so arranged that the springs 12 are located directly above each other in a vertical plane. On the lower end of each shaft 10 are ratchet 75 wheels 13 and 14 controlled by dogs 15 and 16. A magnet 18 operates upon armature lever 17 to advance the ratchet wheels and consequently shaft 10 and disks 11 step by step as impulses flow thru magnet 18.

Loosely mounted upon each shaft 10 adjacent to each disk 11 is an arm 19 which is connected to a spring 20 which acts to normally hold the arm against a fixed stop 21 (Fig. 1) secured to any convenient part of the stationary frame work. Secured to the hub 22, which connects spring 20 to arm 19, and partly wrapped around said hub, is a 80 tape 23. A spring 24 connects the other end of the tape with a rod 25, which rod has its outer end connected to a piston 26 in the air cylinder 27. When compressed air is admitted back of the piston, as will be described later, the outward movement of said piston causes a pull upon the tape which acts to turn the connected arm 19 on shaft 10, and against the action of the connected spring 20, until said arm is stopped by engagement with an associated contact spring 12. The spring 24 between tape 23 and rod 25 permits piston 26 to continue its movement after arm 19 is stopped.

Extending part way around the circumference of the disks 11, and slightly removed therefrom, is a body of insulation 30 in which are embedded contact strips 28 and 29. These strips extend longitudinally parallel with the shaft 10 and have projections extending 110

inward toward said shafts at points on a level with certain contact springs carried on the arms 19. The strips 28 and 29 are arranged in pairs, and the length of the inward projections on strips 28 are shorter than those on strips 29. The spacing of these strips around the shaft 10 corresponds to the spacing of the ratchet wheels 13 and 14, that is the angular distance from one strip 28 to the next strip 28 is equal to the angular distance from one tooth to the next on either of wheels 13 and 14. These strips form contact terminals, and each strip is provided with an outward projection 31 to which a wire may be connected. In Fig. 1 the contact terminals 28 and 29 are represented arbitrarily, as connected to a circle 32.

Pivoted on each arm 19 is a bell-crank lever 33, one end of which is connected to the tape 23, and the other end of which carries two insulated contact springs 34 and 35 adapted to engage projections on strips 28 and 29, respectively. Also pivoted on each arm 19 is a catch lever 36 which is normally held into engagement with the bell-crank lever 33 by a spring 37. (Fig. 2.) When in this position the springs 34 and 35 are held in a retracted position so that they will not engage contacts 28 and 29 when the arm 19 is turned on shaft 10. Insulatingly mounted on lever 36 is a contact spring 38 adapted to engage a contact spring 12 on the adjacent disk 11, and when such engagement occurs, the lever 36 is released from lever 33 so that a pull on tape 23 will turn lever 33 on its pivot to thrust springs 34 and 35 outward into engagement with contacts 28 and 29 as shown in Fig. 2.

40 The insulation 30, which contains the fifty pairs of contact strips 28-29, extends one-half or one-third of the way around the apparatus on shaft 10, and the disks 11 have either two or three springs 12 equally spaced. By this arrangement the shaft 10 does not need to be released to return to a normal position but can be continuously advanced by the magnet 18. The arm 19, however, returns to normal position and, in 45 being advanced by the action of compressed air over the piston 26, strikes one or another of these stopping springs 12. When one of these springs is in a position corresponding to the first pair of strips 28-29, the arm 19 moves only a very short distance from its normal position before it engages the stop spring. As will be explained hereinafter, this engagement with a stop spring 12 closes a circuit for the magnet 18 to move 50 the disk 11 and consequently move the stop spring away from the arm 19, said arm being held from following it by the engagement between springs 34-35 and strips 28-29. Another arm 19 being advanced by 55 its piston 26 engages its corresponding stop

spring at the new position and this in turn completes a circuit for the magnet 18 to again advance the stop springs. At the time when the stop spring is advanced beyond the last pair of contact strips 28-29, 70 another contact spring 12 on the same disk 11 passes under the arm 19 and comes to rest at a position corresponding to the first pair of strips 28-29. To make this possible the contact spring 12 is made as shown 75 in Fig. 9, which will be readily understood by inspection. Electrical contact is made on the front vertical part. The top inclined part is insulated from the spring proper so that a contact 38 in passing over 80 it toward the left will depress the free end without making electrical contact with the disk 11.

The tape 23 (Figs. 7 and 8) has imbedded therein certain flexible insulated conductors. The tape with these conductors in it may be likened to the ordinary telephone cord. The conductors within the tape are connected at one end to the springs 34, 35 and 38, and at the other end to certain other 90 conductors to be hereinafter described.

A shaft 10 has thereon one hundred disks 11 and one hundred corresponding and associated arms 19, each disk with its associated arms being special for a particular 95 subscriber. One such shaft with connected parts forms a sub-group of one hundred line switches for one hundred subscribers, and ten such shafts with their associated parts forms a complete group of one thousand 100 line switches for one thousand subscribers. Each body of insulation 30 (represented by line 32 in Figs. 1 and 9) has in it fifty (more or less) pairs of contact strips 28 and 29, and each contact strip has one hundred inward projections for engagement by 105 the contact springs 34 or 35. The projections on strips 28 and 29 thus furnish one thousand pairs of terminals for each one of fifty trunk lines leading to fifty first 110 selectors.

It is known that ten per cent of trunking is ordinarily sufficient when the subscribers are placed in groups of one hundred. It is also known that a less percentage of trunking is sufficient when the groups are larger than one hundred subscribers, but heretofore there has been considerable difficulty and complication involved in making these larger groups. The present construction takes this fact into consideration and devises apparatus by which the subscribers can be placed in groups of one thousand. In such groups, five per cent of trunking is substantially as 125 efficient as ten per cent of trunking in groups of one hundred. Hence, the system is described as having fifty trunks common for a group of one thousand subscribers.

Parts of the mechanism have already 130

been described. Other parts need no particular description as their structure and operation will be evident in the description of the operation of the exchange when a call is made. Among these other parts is a system of piping and air valves which control a supply of compressed air for operating the pistons 26 in cylinders 27. There is one such piston and cylinder with air control-
10 ling devices for each line switch.

The first line switch (No. 1) has lines A and B leading to a subscriber's station, another line switch (No. 2) has similar lines A' and B' leading to another subscriber's
15 station, and so on. Each pair of lines A—B, A'—B', etc., is connected at the subscriber's station to an ordinary calling device which need not be described as its structure and operation are well known.

20 Assuming that a subscriber is operating the line switch No. 1, shown at the left in Fig. 1, he operates his local devices so as to connect lines A and B together at the station, whereupon a current flows: battery
25 X—40—41—relay 42—B—local station at local station —A—relay 43—X.

The operation of relay 43 breaks connection between contacts 80 and 81, and the operation of relay 42 shifts 45 from contact
30 70 to contact 46. When this last occurs a current flows:—battery Y—44—45—46—47—magnet 48—ground—Y.

The action of magnet 48 moves bell-crank lever 49 and link 50 to swing arm 51 and thus shift the air valves on stem 52 to the right from the position shown. This shift of the valves permits compressed air to flow from a suitable source or supply thru the pipe 53 to the space back of the piston 26 in cylinder 27. The consequent outward movement of the piston acts thru rod 25, spring 24 and tape 23 to turn the attached arm 19 on shaft 10. When the contact spring 38 strikes a contact spring 12 on the
40 associated disk 11, the rotary movement of arm 19 is arrested and the catch 36 is released from lever 33. The pull on the tape 23 then acts upon lever 33 to thrust the contact springs 34 and 35 outward into engagement with projections on the particular strips 28 and 29 which correspond to the position of the spring 12 at the time it was engaged by spring 38.

At the time spring 38 engages stop
55 spring 12, a current flows: battery W—54—brush 55 bearing against any disk on shaft 10 and then thru the mass to spring 12—38—56 in tape 23—57—magnet 18—W. The operation of magnet 18 advances the
60 shaft 10 one step of the ratchet wheel 13 and consequently moves the disks 11 and springs 12 forward one step. This breaks the connection between 12 and 38 and consequently the circuit for magnet 18. It also leaves all
65 of the springs 12 in such a position that if

another arm 19 should be advanced by its piston 26, the contact springs 34 and 35 on that other arm 19 would be projected into contact with the next adjacent strips 28 and 29. Also, this other arm 19 would have its
70 spring 38 engage its associated spring 12 so as to send another impulse thru magnet 18 to advance shaft 10 and disks 11 to a third position. In the same way an advance of a third arm 19 will operate magnet 18 to
75 advance the parts to a fourth position, and so on.

Referring back to the circuit thru magnet 18, and to Fig. 1, it will be seen that there is a branch 57^a running to magnet 18^a of
80 the second sub-group of one hundred line switches, and thence back thru line 58 to battery W. In the same way there are other branches running to corresponding magnets in the other sub-groups of the general group
85 of one thousand line switches. In other words, when any arm 19 in the thousand is advanced and selects a trunk by its spring 38, engaging the corresponding stop 12, a circuit is completed which advances all other
90 stops 12 to a position corresponding to the next trunk in succession.

The stopping of arm 19 in the manner described does not, however, stop the movement of piston 26 under air pressure as
95 spring 24 is interposed for the purpose of permitting a further movement. At the beginning of the outward movement of piston 26, the disk 59 on rod 25 permits contact springs 78 and 77 to close, but as the circuit in which these springs are located is open at 80 by reason of relay 43 being at the time energized, this closure affects nothing at that time. On further advance, a projection 60 on rod 25 presses on a spring 61 on link 50. At this time link 50 is toward the right by action of magnet 48, and the hook 64 on link 50 is in engagement with pin on arm 51. As a consequence the spring 61 yields without depressing link 50 so as to
100 release arm 51.

On further outward movement of piston 26 the insulated extension of rod 25 engages spring 40 to break its connection with spring 41, and immediately thereafter the disk 59 engages and passes under a hook 62 on spring actuated arm 63. Opening springs 40—41 breaks the circuit for relay 42, whereupon armature 45 falls back and breaks the circuit for magnet 48. When
115 this circuit is broken spring 65 acts on arm 51 to shift the air valves on stem 52 back to the position shown in the drawings. This closes the opening to the supply pipe 53 and opens the exhaust for the space back of the piston 26. The engagement between hook 62 and disk 59, however, prevents return of the piston at this time. With link 50 and arm 51 in the position shown with hook 64 free from pin on arm 51, the pressure of
120
125
130

projection 60 on spring 61 will move link 50 downward so that its hook 66 will engage hook 67 on arm 63. These parts remain in this position during the further operation 5 of apparatus in the process of calling a subscriber, and during conversation.

When springs 34 and 35 were projected outward into engagement with a pair of strips 28-29 they made connections to a 10 trunk line leading to a first selector. First selectors as now constructed and installed in automatic telephone exchanges have one branch of the trunk leading thereto connected thru a relay to a battery and ground. 15 This connection establishes a circuit for relay 43 so that when the circuit for relay 42 was broken by the opening of springs 40-41 there was another circuit previously established for relay 43. This other circuit 20 is as follows: ground-43-A-telephone-B-68 thru tape 23 to spring 35-selected strip 29 and trunk connected thereto-relay in first selector on end of trunk-battery-ground. The relay 43 is of the type known 25 as "slow relay" and will hold its armature attracted during the time when further impulses are flowing for the operation of selectors and connectors. If the next trunk is busy there will be an arm 19 with its contact 30 spring 38 at that position. Fig. 9 shows a standing spring 38 with the disk 11 and its spring 12 in a position to be moved to the right under the spring 38. In passing under spring 38, the spring 12 is deflected 35 downward and then rises making electrical connection with 38 while rising. This electrical connection sends another impulse thru magnet 18 to advance the apparatus another step.

40 As previously described, the magnet 48 of line switch No. 1 was operated from battery Y by relay 42 moving armature 45 into contact with 46. In the same way, the magnet of line switch No. 2 would be operated by 45 the relay 42 of that switch moving 45 to contact with 46. To make this possible, armature 45 of switch No. 1 must be against its back contact 70, which in this case is represented as a mercury cup to reduce resistance. Similarly, to make it possible for 50 magnet 48 of switch No. 3, or any later one in the entire series of one thousand switches, the armatures 45 of all intermediate switches back to battery Y must be against 55 their back contacts.

When subscriber No. 1 is calling, the first operation energizes relay 42 to cut off calls by all other subscribers in the thousand until No. 1 has seized an idle selector and the 60 movement of his piston 26 has broken the circuit for relay 42 at 40-41. It is during this interval that all disks 11 on the one thousand are being advanced one step, and it is inadmissible that two subscribers 65 should be simultaneously advancing the

same apparatus. As soon as armature 45 of No. 1 falls back connection is completed so that relay 42 of No. 2 (or any later number) may close for 48 of that station. When this occurs No. 2 holds the connection against 70 No. 3 and later numbers by having his connection open at 70 until he has seized an idle selector and opened his contact springs 40-41. Similarly, No. 3 would hold the connections against No. 4 and later numbers, No. 75 4 would hold them against No. 5 and later numbers, and so on.

When No. 2 is calling he holds the connections against all subsequent numbers by having his contact 70 open, but he does not hold it against No. 1 in the same way because No. 1 is between him and battery Y. The same result, however, is accomplished in another way. The battery Y is made of such strength and relationship to the magnets 48 that it furnishes current enough to operate one of them but not two of them at the same time. Thus, if No. 2 calls first and gets current on his magnet 48 from battery Y, then if No. 1 comes in during the brief 80 time while a selector is being selected and the contacts 40-41 of No. 2 are closed, the closure of the circuit for 48 of No. 1 will not cause that magnet to operate until 40-41 of No. 2 is opened. To prevent the relay 95 42 of No. 1 from breaking the circuit for 48 of No. 2, that switch, and all other switches except No. 1, is provided with a shunt which 100 48 closes for itself until 42 of No. 2 is deenergized. This shunt circuit is; Y-71-72-73-74-75-76-45-46-47-48-ground-Y. The springs 73-74 are on all line switches except No. 1.

When the calling subscriber has finished his conversation he hangs up his receiver. 105 The ordinary local station apparatus is so constructed that hanging up the receiver breaks the connection at the station between lines A and B. The lines A and B form part of the circuit for relay 43, and breaking the connection between them breaks the circuit for this relay. When this occurs the armature 81 falls back against the contact 80 whereupon a circuit is completed as follows: battery Z-77-78-79-80-81-82-48-ground-Z. The action of magnet 48 moves link 50 to the right to pull catch 62 from disk 59 so that piston 26 and arm 19 may be returned to normal position by the action of spring 20. At this time the hook 120 64 is below pin on arm 51 and passes under said pin without moving the arm 51 to shift the air valves. Just before the piston 26 reaches its normal position disk 59 engages spring 78 to open the circuit for magnet 48. 125 In returning to normal position, hook 64 on link 50 passes under the pin on arm 51.

It will be seen from the foregoing that I provide a group of one thousand line switches, more or less, which form a unit 130

but which, for convenience of construction, I divide into ten sub-groups of one hundred each. Each subscriber has in the apparatus a pair of contact makers which are individual for his use and which, when not in use, stand at a normal position. All of the rest of the apparatus of the line switches, when not in motion, stand opposite the first idle trunk leading to an idle selector. When a calling subscriber advances his contact makers they are projected into engagement with this trunk and a circuit is closed which advances the rest of the apparatus to a position opposite the next idle trunk. By providing a plurality of stops 12 for each subscriber I am enabled to confine the trunk terminals to a small space without making it necessary to return the general apparatus to a normal position at intervals.

When a line remains busy for some time and a disk 11 advances far enough for a spring contact 12 to pass under the spring 38 of the busy line, the said spring 38 touches the contact 12 and completes a circuit for the magnet 18 to advance the disk 11 another step. In this case the advance is by a spring 12 catching up the stationary spring 38 and not by a new call being made.

What I claim is:

1. In a trunking selecting device, a series of trunk terminals a wiper carrier operated pneumatically to extend connections to idle trunk lines, a master device operated electrically to a position always in alignment with an idle trunk, and means controlled by the master device for stopping said contact carried opposite said trunk when the contact carrier is operated.

2. In a telephone system, a series of lines, a series of trunk selecting switches, one for each line, a common shaft carrying all of said line switches, a master stop for each line switch mounted on said shaft, automatic means for rotating said shaft to maintain said stops in alignment with idle trunk lines, and a pneumatic device for operating each line switch to connect with the trunk preselected by its stop.

3. A shaft having a stopping device secured thereto, a magnet and devices for advancing the shaft and stop step by step, a series of contact terminals adjacent to the path of the stop and spaced to correspond to the step by step movement of the stop, an arm pivoted upon the shaft and movable from a normal position to engagement with the stop, devices on the arm arranged to be automatically projected into engagement with a contact terminal when the stop is engaged, and an electric circuit for said magnet closed by engagement with said stop.

4. A plurality of stopping devices and means for moving them step by step about a central point, contact terminals adjacent

to the path of the stops and extending over a distance equal to the angular distance between one stop and the next, an arm movable about the center to contact with a stop, and means by which such contact causes the arm to engage and be held by an adjacent terminal.

5. A shaft having a plurality of disks secured thereon, devices for advancing the shaft step by step, a stop on each disk, said stops being in line with each other, contact strips arranged around said shaft and each projecting inward adjacent to said disks, an independently movable arm pivoted upon the shaft adjacent to the face of each disk, devices for each arm for moving it from its normal position to contact with a stop on the adjacent disk, and means by which such contact causes the moved arm to engage the contact strip corresponding to the position of the stop at the time the arm was moved.

6. The combination with a large number of independently movable contact makers and a less number of trunk lines each having a contact terminal adjacent to the path of each contact maker, of means for moving any contact maker from its normal position over a space represented by terminals for all trunk lines, means for arresting the moving contact maker opposite the terminal of the first idle trunk and for causing a further movement to bring about engagement between the two, and means for preventing a second contact maker being similarly moved prior to the completion of such engagement.

7. The combination with a large number of contact makers each normally held at a normal position, and a less number of trunk lines each having terminals located at varying distances from the normal position of each contact maker, of means for moving any contact maker from its normal position to engagement with a terminal of an idle trunk, and means for preventing any other contact maker being moved from its normal position during the interval in which the first contact maker was moving.

8. The combination with a large number of pairs of contact makers each normally held at a normal position, and a less number of pairs of trunk terminals adjacent to the path of each contact maker, of independently operable devices for moving each pair contact maker from its normal position to engagement with the terminals of an idle trunk, means associated with the beginning of the operation of each of said devices for breaking the operating connections for the other devices, and means associated with the completion of a movement of a pair of contact makers for re-establishing the operating connections for the said other devices.

9. In a telephone exchange, the combination with a large number of contact carriers, and a less number of trunk lines having terminals adjacent to the path of each carrier, of a separate power device for moving each carrier from its normal position to engagement of its contacts with the terminals of an idle trunk, lines leading to substations and serving as means by which a subscriber at any such station may start his power device to move its carrier, and electrical connections so arranged that upon starting one power device into operation the other power devices will be restrained from operation until the first power device has completed the movement of its carrier to establish connections with an idle trunk.
10. In the trunk selecting mechanism of a telephone exchange, a power device having a predetermined movement, a contact carrier having a variable movement by which connection is established with one of a number of trunk lines, and a yielding connection between the power device and the carrier by which the early stopping of the carrier does not limit the movement of the power device.
11. A contact carrier, a power device for moving said carrier from its normal position, a series of trunk terminals, a stopping device located in the path of the carrier, means for shifting the position of the stopping device from time to time so as to maintain it opposite the terminals of an idle trunk, and a yielding connection between the power device and the carrier.
12. A series of contact terminals, a contact carrier, a power device for moving the carrier over the entire series of terminals, means for stopping the carrier at an intermediate point to bring about engagement with an intermediate terminal, a yielding connection between power device and carrier so that a stoppage of the carrier does not stop the power device, and an electrical controlling device operated by the terminal part of the movement of the power device.
13. A shaft having a stopping device secured thereto, a power device and connections for advancing the shaft and stop from a position of rest, a series of contact terminals adjacent to the path of the stop, an arm pivoted upon the shaft and movable from a normal position to engagement with the stop, devices on the arm arranged to engage a contact terminal when the stop is engaged, and automatically operating means for starting the power device into operation when the stop is engaged by the arm.
14. Contact makers, a flexible connection serving to move said contact makers, a magnet for controlling their movement, and an electrical conductor embedded in said flexible connection and serving as part of the electrical circuit for said magnet.

15. The combination with a contact carrier, and a pneumatic motor for moving it from normal position, of a stop for arresting the carrier, a power device for moving the stop so that it will not arrest some other carrier at the same position, and means for controlling said power device by the stoppage of the carrier.

16. In a switching mechanism, a series of stops movable from position to position, a series of arms each movable to engagement with a stop in stationary position, means by which upon a stop being engaged by an advancing arm said arm will be arrested and the stop advanced to its next position, and means by which upon a stop overtaking an advanced arm the said stop will be deflected to pass under the arm and will then complete a connection for causing the stop to be advanced to its next position.

17. The combination with a series of contact carriers, and a corresponding series of pneumatic motors for moving them independently from normal position, of stopping devices for arresting the carriers when so moved, power means for moving the stopping devices so that two carriers will not be stopped at the same position, and means by which the stoppage of a moved carrier causes an operation of the power means.

18. The combination with a series of contact carriers, and pneumatic devices for moving them independently from normal position, and automatic means controlled by the stoppage of one carrier for moving the stopping devices so that another carrier will not be arrested at the same position.

19. The combination with a large number of contact makers each normally held at a normal position, and a less number of trunk lines each having terminals located at varying distances from the normal position of each contact maker, of means for moving any contact maker from its normal position to engagement with a terminal of an idle trunk, means for preventing any other contact maker being moved from its normal position during the interval in which the first contact maker was moving, and a relay for controlling both of said means.

20. The combination with a large number of contact makers each normally held at a normal position, and a less number of trunk lines each having terminals located at varying distances from the normal position of each contact maker, of means for moving any contact maker from its normal position to engagement with a terminal of an idle trunk, means for preventing any other contact maker being moved from its normal position during the interval in which the first contact maker was moving, a relay for controlling both of said means upon its initial energization, means for returning said contact maker to normal position, said last

means controlled by said relay upon its second energization.

21. In a trunk selecting mechanism of a telephone exchange, a contact carrier having a variable movement by which connection is established with one of a number of trunk lines, a power device for moving said contact carrier and having a predetermined movement, and a yielding connection between the power device and the contact carrier which permits said power device to continue its movement to its predetermined position after said contact carrier has been stopped.
- 15 22. A contact carrier, a power device for moving said carrier from its normal position by a continuous or single movement, a series of trunk terminals, a stopping device

located in the path of the carrier, means for shifting the position of the stopping device 20 from time to time by a step by step movement so as to maintain said stopping device opposite the terminals of an idle trunk, and a yielding connection between the power device and the carrier.

25 23. A plurality of stopping devices and means for moving them step by step, contact terminals adjacent to the path of the stopping devices and extending over a distance equal to the distance between one stopping device and the next, an arm movable to make contact with a stopping device, and means for causing the arm to engage and be held by an adjacent terminal.
